UNITED STATES PATENT OFFICE.

FRANK STEWART, OF CHICAGO, ILLINOIS, ASSIGNOR TO THE STOCKHAM MANUFACTURING COMPANY, OF SAME PLACE.

DESIGN FOR A FURNITURE-FOOT.

SPECIFICATION forming part of Design No. 28,709, dated May 24, 1898.

Application filed March 25, 1898. Serial No. 675,188. Term of patent 7 years.

To all whom it may concern:

Be it known that I, FRANK STEWART, a citizen of the United States, residing at Chicago, in the county of Cook and State of Illinois, 5 have invented and produced a new and original Design for a Furniture-Foot, of which the following is a specification, reference being had to the accompanying drawings, forming part thereof.

Figure 1 is a view in front elevation of a furniture-foot, showing my new design; and Fig. 2 shows the same by a view in side elevation.

The more immediate purpose for which I 15 have devised my new design is that of a foot for piano-stools and tables, though it is also applicable to other articles of furniture.

As shown in the drawings, the leading or material feature of my design consists in the 20 grotesque representation on the socket-piece for receiving the leg of a piece of furniture of an imaginary animal clinging to a glass or

other ball in accordance with the disposition or arrangement shown in the figures of the drawings. The ball G is represented as let 25 into the head II and body B of the animal, which partly envelops it, with claws C and a tail T clinging to the ball. The body of the animal is covered with the "modern Italian renaissance" style of leaf ornamentation O, 30 which is extended to produce a harmonious effect up along the shank portion of the socket-piece S. About the edge of the mouth of the socket-piece is provided a row of beads r.

Having described my invention, what I 35 claim as new, and desire to secure by Letters Patent, is—

The design for a furniture-foot, as herein shown and described.

FRANK STEWART.
